CAR CONSTRUCTION

William M. Dwyer, Chicago, Ill., assignor to
 W. H. Miner, Inc., Chicago, Ill., a corporation
 of Delaware

Application January 11, 1935, Serial No. 1,278

4 Claims. (Cl. 105—454)

This invention relates to improvements in car construction.

One object of the invention is to provide in a railway car structure, means located at opposite ends of the car yieldingly embracing the lading and reacting between the car structure and lading to absorb shocks imparted to the latter in directions lengthwise of the car due to starting and stopping of the car and sudden changes in speed thereof, thereby protecting both the car structure and the lading from damage.

Another object of the invention is to provide means of the character indicated in the preceding paragraph, in the form of resilient end members on the railway car, especially adapted for use in connection with lading in the form of a plurality of freight container units.

Still another object of the invention is to provide shock absorbing means in the form of abutment members respectively at opposite ends of a railway car, which abutment members are forced inwardly toward each other, by yielding means, to embrace and clamp therebetween a plurality of freight container units arranged in series lengthwise of the car and cushion said container units against shocks, said abutment members being adjustable away from each other lengthwise of the car against the pressure of said yielding means to temporarily effect spreading apart of said members to permit loading of groups of different sized containers therebetween, said members being returned to clamping condition by the action of the yielding means.

A more specific object of the invention is to provide in connection with a shock absorbing means of the character described in the preceding paragraph, mechanism for adjusting the abutment members toward and away from each other and temporarily holding the same in any desired position of adjustment while subject to the influence of the cushioning action of the yielding means.

Other objects of the invention will more clearly appear from the description and claims hereinafter following.

In the drawing, forming a part of this specification, Figure 1 is a part top plan view and part horizontal sectional view of one end portion of a railway car, illustrating my improvements in connection therewith, said view being partly broken away, and the horizontal section corresponding substantially to the line 1—1 of Figure 3. Figures 2 and 3 are longitudinal, vertical sectional views, corresponding respectively to the

lines 2—2 and 3—3 of Figure 1. Figure 4 is a transverse, vertical sectional view, partly broken away, corresponding substantially to the line 4—4 of Figure 2, said view being to one side of the center line of the car.

In said drawing, 10 indicates a portion of the end structure of the underframe of the car. The underframe structure 10 includes center sills 11—11, and end sill 12, and side sills, said center, end, and side sills being shown as formed of a single casting and integral with the underframe structure proper of the car. One of the side sills only is shown, the same being indicated by 13 in the drawing. The underframe structure 10 is also provided with diagonal braces, one of which is shown and indicated by 14. Floor braces are also employed extending between the center sills and the diagonal braces 14, one only of said floor braces being shown, the same being indicated by 15. The center sills are provided with the usual stop lugs 16—16 and 16—16 and the end sill has a striking face 17 which cooperates with the usual coupler 18. The shock absorbing mechanism of the railway car and cooperating elements are not shown in the drawing. The end sill 12 has the usual vertical web 19 and top and bottom, inwardly extending, horizontal flanges 20—20.

My improvements comprise broadly a sliding end member A at each end of the car; springs B—B and B—B opposing outward movement of the end member; and combined adjusting and holding means C—C cooperating with the end member for moving the same outwardly against the pressure of the springs and temporarily holding said end member in adjusted position.

In carrying out the invention, I provide each of the end sills with two sets of spaced, vertical webs 21—21 and 21—21, thereby providing spring pockets 22—22 at opposite sides of the end of the car. Each pocket is defined by the webs 21—21 and the top and bottom flanges 20—20 of the end sill 12.

The sliding end member comprises a shelflike portion 23 extending from one side to the other of the car, a vertical abutment wall 24 at the forward edge of said shelf 23, and a pair of depending spring abutments 25—25 between the front and rear ends of said shelf 23. Each abutment 25 is formed by a transverse vertical wall 26 and bracing side webs 27—27 of substantially triangular outline, as clearly shown in Figure 3. The webs 27—27 are formed integral with the shelf portion 23. As most clearly shown in Figures 2 and 3, the central portion of the shelf is

slightly raised with respect to the front portion thereof, said raised section being indicated by 28. The raised section 28 has the upper surface thereof disposed substantially in the plane of the lading supporting portion of the car. The shelf is also provided with depressed rearward extensions 29 at opposite sides thereof which engage beneath the corresponding floor braces 15, thereby preventing upward tilting of the rear end of 10 said end member A. The depressed forward end section of the shelf 23 of the end member A is slidably supported on the top flange 20 of the end sill 12 and on the center sills 11-11. As most clearly shown in Figure 3, the central section of 15 the wall 26 of the spring abutment 25 is thickened, and said thickened section is provided with a transversely curved seat, as indicated at 30.

The springs B-B and B-B are arranged in pairs at opposite sides of the end of the car, each 20 pair being contained in the corresponding spring pocket 22. Each of the springs B has its front and rear ends bearing respectively on the inner side of the vertical web 19 of the end sill 12 and the wall 26 of the corresponding spring abutment 25.

The combined adjusting and holding means C-C cooperate with the spring abutments 25-25 at opposite sides of the end of the car. Each 30 combined adjusting and holding means C comprises a bolt 31 headed at the forward end, as indicated at 32. The head of the bolt 31 has an opening 33 therethrough, adapted to receive an operating bar by which the bolt may be rotated to adjust the same. The head 32 of each bolt 35 is also provided with an annular flange 34 at the inner end which bears on the outer side of the vertical web 19 of the end sill 12. The bolt 31 extends between the springs B-B at the corresponding side of the end of the car and has its 40 rear end threaded, as indicated at 35. A nut 36 is mounted on the threaded portion 35 of the bolt and has a transversely curved bearing face 37 which engages in the curved seat 30 so that the bolt may angle laterally with respect to the longitudinal axis of the car. A locking element 45 in the form of a small bolt 38, extending through the inner end of the shank of the bolt 31, serves to prevent accidental removal of the nut 36 from the bolt 31. When the bolt is turned, the nut 50 36 is held against rotation by the flat top and bottom faces thereof engaging the straight top and bottom walls 39-39 of the seat 30. As shown most clearly in Fig. 3, the threaded portions of the bolts are of sufficient length to permit full outward adjustment of each member A to a position where movement thereof is limited by engagement of the wall 26 with the inner edges of the flanges 20-20 of the corresponding end sill. The parts are so proportioned that the 55 outward movement of the end member A is stopped by the shouldered engagement of the wall 26 with the flange 20 of the end sill at a point where the abutment wall of the end member A is spaced inwardly from the front or outer face of the end sill 12 of the car. Thus the end member is at all times within the outer limits of the 60 end of the car and movement of said end member in no wise interferes with the clearance limits prescribed in modern railway practice.

As will be evident, the construction of the end members A-A and cooperating parts is the same at the opposite ends of the car and the end members serve as yielding shock absorbing means to absorb the shocks imparted to the lading which is disposed between the abutment

walls 24-24 of said end members A-A. Upon a shock being imparted to the lading of the car, the lading will be projected against either of the end members A, thereby moving said end member outwardly against the resistance of the cooperating springs B-B and B-B. The springs are of sufficient capacity to restore the end member to its original position. In loading a car with container units, the units are arranged in series in one or more groups, each group extending 10 lengthwise of the car between the abutment members A-A. The abutment members A-A are preferably so arranged and designed that they exert a yielding pressure on the opposite ends of the series of container units at all times, 15 thereby preventing damage to the containers, which might otherwise occur due to the containers being spaced apart with respect to each other. As will be evident adjustment of the end members serves to increase or decrease the distance between said members thus allowing for differences in overall length of different groups of containers due to difference in sizes of containers comprised in said different groups.

In loading a car, the operation of my improved mechanism is as follows: Either one or both of the abutments A-A of the car are adjusted outwardly to an extent to permit the placing of the series of container units therebetween. The outward movement of each end 30 member A is effected by adjusting the bolts 31-31. In adjusting each bolt 31, the nut 36 thereof is screwed on to the bolt, thereby pulling the abutment end member A outwardly. As will be evident, the sliding rocking engagement 35 of the nut 36 of each adjustable bolt 31 on the bearing seat of the corresponding spring abutment member 26 of the end member A permits adjustment of the bolts independently without binding thereof as the bolts may angle laterally. When the series of containers has been loaded between the end members A-A, the bolts 31-31 are adjusted in a reverse direction, thereby permitting the springs B-B and B-B to move the end member A against the adjacent 45 container of the series. As will be evident, the containers are thus yieldingly clamped between the end members A-A at opposite ends of the car.

I have herein shown and described what I now consider the preferred manner of carrying out my invention, but the same is merely illustrative and I contemplate all changes and modifications that come within the scope of the claims appended hereto.

I claim:

1. In a railway car including an underframe structure provided with horizontal floor braces, the combination with an end member at each end of the car slidably supported on said underframe; of yielding means reacting between the underframe structure and each end member to yieldingly oppose outward movement of said end member; and a guide shelf on each member slidably engaged underneath the floor brace at the corresponding end of the car.

2. In a railway car including an underframe structure provided with a horizontal floor brace at each end of the car, the combination with sliding abutment members at opposite ends of the car, said abutment members having shouldered engagement with said floor braces to limit inward movement of said members; of yielding means opposing outward movement of said abutment members.

3. In a railway car body comprising supporting means extending lengthwise thereof for supporting a group of freight containers arranged in series lengthwise of the car, the combination with an end member on the car including a container supporting section and a transverse wall rigid therewith; of guide means slidingly supporting said member at the end of said supporting means; stop means for limiting outward movement of said end member to a position within the end limits of the car body; a fixed abutment on the car; shock absorbing spring means interposed between said end member and the fixed abutment means yieldingly opposing outward movement of said end member; and means for adjusting said end member outwardly and inwardly to conform with different sizes in length of container groups, said adjusting means including an outwardly and inwardly movable element having outward pushing contact with said end member and a screw member for adjusting said movable element, said screw having a projecting operating head portion exterior of the end of the car.
4. In a railway car, the combination with an underframe structure including transverse end sills; of a sliding end member at each end of the car spaced inwardly from the outer limits of said end sills, each end member having an abutment wall for the lading of the car; yielding means opposing outward sliding movement of each end member; combined adjusting and holding means for spreading said members apart lengthwise of the car to accommodate different over-all lengths of lading therebetween, permitting further outward yielding of said members, and for holding said members against inward movement from said adjusted position; and stop means for limiting outward movement of said end members to a position spaced inwardly from the outer limits of said end sills.
